UNITED STATES PATENT OFFICE.

EDGAR L. MILLER, OF GUNNISON, COLORADO.

PUNCH.

1,306,920.

Specification of Letters Patent. Patented June 17, 1919.

Application filed March 14, 1917, Serial No. 154,825. Renewed April 7, 1919. Serial No. 288,221.

To all whom it may concern:

Be it known that I, EDGAR L. MILLER, a citizen of the United States, residing at Gunnison, in the county of Gunnison and State of Colorado, have invented certain new and useful Improvements in Punches, of which the following is a specification.

This invention relates to paper fasteners of that class in which the paper is cut and bent over to hold the sheets together without fastening devices of any kind.

The principal object of the invention is to provide a device of this nature which will punch the paper and bend it over by one movement of the hand.

Another object of the invention is to provide holding means for clamping the sheets of paper in position while being punched.

Another object of the invention is to provide a device of this character which is simple and durable in construction, reliable and efficient in operation and one which can be manufactured and placed upon the market at a minimum cost.

To accomplish the above and various other objects, my invention consists essentially of a punch operated by a handle to punch the paper, of a member operated by the said handle for bending the punched out portion of the paper upon the sheets of paper and of holding means for holding the sheets in place while the above described operations are taking place.

The invention also consists in certain other features of construction and in the combination and arrangement of the several parts to be hereinafter more fully described and specifically pointed out in the appended claims.

In describing my invention in detail, reference will be had to the accompanying drawings, wherein like characters denote like or corresponding parts throughout the several views, and in which:

Figure 1 is a side view of the invention.

Fig. 2 is a longitudinal section.

Fig. 3 is a plan view.

Fig. 4 is a section on the line 4—4 of Fig. 1.

Fig. 5 is a bottom view, with the supporting plate removed.

In these drawings, 1 is the supporting plate on which the punch proper is held by the screws 2. The frame of the punch consists of the bottom part 3, the head 4 and the connecting part 5. A plunger 6 is

mounted in the head and is provided with a cutting member 7 which is screwed into the lower part of the plunger. The plunger is provided with a head part 8, against which 60 engages a spring 9 for normally holding the cutter out of engagement with the paper. 10 is a rotating member pivoted in the punch head and provided with striking arms 11 for engaging the top of the plunger for 65 depressing the same. This member is caused to rotate by means of the handle 12 being pivotally mounted upon the axle of the rotating member and being provided with a spring pressed plunger 13 for engaging 70 the arms 11.

The plunger is provided with a removable head 14, so that the same can be removed when worn and replaced by a new one. The base portion 3 is provided with 75 a die plate 15 provided with an opening 16 through which the cutter 7 passes.

The device for bending over the paper as the same is punched consists of a plate 17 pivoted at 18 to a lever 19, pivoted at 20 to 80 the connecting part 5 of the frame and has its upper end curved at 21 to come in contact with an inclined part 22 of the handle 12.

Said lever 19 is held in vertical position 85 by a spring 23 secured to its lower end, said spring having its other end secured to a hook 24 carried by the base 3. The free end of the plate 17 rests on lugs 25 forming part of the base 3 and this plate is caused to move 90 upwardly at the end of its forward movement by means of a curved projection 26 on the bottom of the plate, coming in contact with the lugs 25 so as to raise the plate. The plate is provided with a projecting head 95 27 about midway of its ends, and said head is of substantially the same size as the width of the slot 16 in the die plate, so that as the plate 17 moves forward and upward the said head is caused to pass into the said slot 16. 100

To provide means for clamping the papers in position, I provide a handle 28 pivoted at 29 to the head of the punch and to this handle I pivot a plate 30, said plate resting on the die plate above the outer end of the slot 105 16 when the handle 28 is lowered.

31 is an adjustable stop secured to the die plate by the screw and slot connection 32.

The sheets of paper 33 to be connected together are placed on the die plate and the 110 handle 28 depressed so as to bring the plate 30 on the sheets of paper, as shown in Fig.

1. The handle 12 is then raised until the plunger 13 passes one of the arms 11 of the member 10. The handle 12 is then pushed backwardly and downwardly so that the 5 plunger 6 is depressed by one of the arms 11 on the member 10 and the cutter 7 passes through the sheets of paper and forces the punched out portions into the slot 16. On the further movement of the handle 12 the 10 arm 11 leaves the plunger head, allowing the same to spring back, while the handle comes into engagement with the lever 19 and rocks the same on its pivot, thus causing the plate 17 to move forwardly so that the head 27 engages with the punched out 15 portions of the sheets and pushes them backward, and then as the curved projection 26 strikes the lugs 25, the plate with its head is caused to rise, thus forcing the punched 20 out portions of the sheets hard against the plate 30, so as to securely connect the sheets together.

It will be seen that the head 27 not only 25 folds the punched out portions of the paper back upon itself, but it also forces such punched out portions through the slot 16 so that the sheets can be removed when the handle 28 is raised.

It is thought from the foregoing that the 30 advantages and novel features of my invention will be readily apparent.

I desire it to be understood that I may 35 make slight changes in the construction and in the combination and arrangement of the several parts, provided such changes fall within the scope of the appended claims.

I claim as my invention:

1. A punch for fastening sheets of paper together, comprising a vertically movable 40 plunger having a cutter head thereon, a die plate coöperating with the said head to punch out a tongue in said paper, a horizontally movable head below the die plate for bending the punched out tongue of the 45 paper, means for giving said horizontally movable head an upward movement to further bend the tongue against the body of the paper and a handle for operating the plunger and the bending head.

50 2. A punch for securing sheets of paper together, comprising a plunger, a cutter head thereon, a die plate coöperating with the cutter head to punch out a tongue in said paper, a horizontally movable plate

below the die plate, a head thereon for engaging with the punched out tongue of the paper, means on said horizontally movable plate engaging with a part of the frame to give said plate vertical movement at a certain part of its horizontal movement and 55 means for operating the plunger and plate. 60

3. A punch comprising a base portion having a slot therein, a head portion located above the base portion, a plunger operating in said head portion and adapted to coöperate 65 with the slot in the base portion for slotting sheets of paper, means for reciprocating the plunger, a handle pivoted to the head portion and a plate pivoted to said handle and adapted to hold the sheets on 70 the die-plate.

4. A punch comprising a base portion having a slot therein, a head portion above the base portion and a connecting portion connecting the head with the base, a plunger 75 mounted in said head and having its lower end adapted to coöperate with the slot in the base portion, a horizontal movable plate in the base portion, a vertical lever pivoted in the connecting portion and having its 80 lower end pivoted to the said plate, a support on which the free end of the plate rests, a curved projection on the bottom of the plate contacting with the support when the plate is moved horizontally, a head located on the plate and adapted to engage the slot in the base, rotatably mounted contacting arms for the plunger and a handle for rotating said arms and engaging with the vertical lever to actuate the horizontally 85 movable plate.

5. A punch including a spring pressed plunger, rotatably mounted arms for contacting with and depressing the plunger, and means for rotating said arms. 95

6. A punch including a spring pressed plunger, rotatably mounted for contacting with and depressing the plunger, a handle for rotating said arms and a catch associated with said handle for engaging with and rotating said arms. 100

In testimony whereof I affix my signature in presence of two witnesses.

EDGAR L. MILLER.
